UNITED STATES PATENT OFFICE.

ANDREW C. PREBLE, OF CHICAGO, ILLINOIS.

LATCHING MEANS.

Application filed May 8, 1924. Serial No. 711,830.

To all whom it may concern:

Be it known that I, ANDREW C. PREBLE, a citizen of the United States, residing at Chicago, in the county of Cook and State 5 of Illinois, have invented certain new and useful Improvements in Latching Means, of which the following is a specification.

This invention relates particularly to a latching means for fire doors or emergency 10 exists in which it is customary to specify latching or locking means which will automatically yield to pressure from the inside of the door and which at the same time may be provided with suitable handle mechanism 15 for unlatching the door from the outside.

The object of the present invention is to construct a latching mechanism of the character indicated which shall be simple and compact in structure and so located in respect to the free edge or unhinged edge of 20 the door as to permit of easy and convenient unlatching and swinging of the door either by direct thrust from the inside or by direct pull from the outside. Since metallic fire 25 doors are commonly quite heavy or ponderous, it is desirable to locate the latching mechanism close to the free edge of the door which permits the door to be readily opened; and it is also desirable to avoid the use of 30 mechanism which require a lifting movement to effect unlatching in advance of a retractive opening movement. The present invention conforms to the above requirements.

35 In the drawings:

Figure 1 is an elevation of the outside of a door showing in full lines the latching mechanism in latched relation, and in dotted lines the position of the parts when in unlatched relation;

40 Fig. 2 is an inside view of the latching mechanism;

Fig. 3 is an enlarged sectional plan view taken on lines 3—3 of Fig. 1; and

45 Fig. 4 is a sectional elevation of a portion of the latching mechanism taken on line 4—4 of Fig. 3.

The fire door 10 is mounted on hinges 11 which are secured to a casing 12 which surrounds the door opening. The door in the form shown consists of a metallic plate which is preferably reinforced near its margin by a reinforcing strip of angle iron 13, the body of the door projecting beyond the 50 strip and preferably overlapping the inner edge of the casing. The details of the door

construction are, however, relatively unimportant since the latching mechanism is applicable to doors of various constructions.

Near the free edge of the door on the outer 60 face thereof is located the latch bar 14 which is pivoted at its inner end to a pin or rivet 15, and the free edge of the latch bar projects beyond the proximate edge of the door in position to engage with a notched strike 65 plate 16 which projects outwardly from the door casing at the proper point. An offset strap 17 is provided to act as a guide for the latch bar and permit sufficient lifting movement to free the latch bar from the 70 strike plate. In the form shown, the latch bar, strike plate, and guide strap are arranged in triplicate, so that the door will be latched near the top and bottom and also at 75 the center.

In order to provide for uniform movement of the three latch bars, a single connecting link 18 is employed which is hinged in each instance to a pin or stud 19 extending outwardly from each of the latch bars. 80 The pin 19 of the center latch bar has pivoted thereto an operating link 20 which extends obliquely downward and makes connection with a slide bar 21, the link being provided with a slot 22 which engages with 85 a pin 23 to afford a certain amount of such motion under circumstances to be presently explained.

The slide bar at its outer end is provided with a guide slot 23 which engages with a 90 pin or roller 24, and the inner end of the slide bar is slidably entered between a pair of outstanding ears 25 formed on a plate 26 which is screwed to the face of the door in proper relation to the metal latch bar 95 to afford the requisite amount of lift when the latch is operated. The slide bar terminates at its rear end in an outstanding lug 27, the rear face of which is adapted to be engaged by a curved finger 28 which constitutes the rear extension of a handle 29 which is pivoted near its rear end upon a cross pin 30 which extends between the ears 25, the arrangement being such that as the handle is drawn back to the position indicated by dotted lines in Fig. 3, the finger 28 will be forced forwardly against the lug on the slide bar, thereby moving the slide bar and imparting a thrust through the pin 23 against the obliquely disposed link 20 100 which will accordingly be swung into the dotted line position of Fig. 1 to effect a 105 110

lifting of all three of the latch bars. In order to restore the slide bar to its retracted position, the slide bar is provided with a depending tongue 31 to which is secured a spring 32 which is connected to a pin 33 on the plate 26.

The above constitutes the mechanism provided for operating the door from the outside, but in order to effect an operation from the inside, the following mechanism is provided: At a point underlying the slide plate, the door is provided with a slot 34 through which extends a lug 35 carrying a pivot pin 36 which pivot a link 37 the rear end of which is connected to the short arm 38 of a bell crank lever 39, the long arm of which terminates in a flattened contact plate 40 of sufficient dimensions to afford an extended surface for the application of pressure which may be exerted from the inside of the door, either in the ordinary opening or in case of emergency and panic. The bell crank lever 39 is pivoted to a cross pin 41 carried between ears 42 of an inner bracket plate 43 which occupies a position immediately opposite to the outer bracket plate 26, the two plates being of substantially uniform dimensions and secured in place by bolts 44.

30 The operation of the device is as follows: Where the door is to be opened from the outside, a retraction of the handle arm 29 will first impart a movement to the slide plate which in turn will effect a lifting of the latch bars, and thereafter a continued pull on the handle in the same outward direction will swing open the door, which continuous pull on the handle in one and the same direction is highly advantageous in the openings of ponderous doors and is superior to methods which require an unlatching movement in one direction and a door swinging movement in a different direction. In operating the door from the inside, a thrust on the contact plate 40 will likewise effect an unlatching of the door and an opening thereof by a continuous movement in an outward direction, and in the event of fire or panic, the door will open automatically when pressure is exerted upon the latching mechanism.

55 The compact arrangement of the latching mechanism is such as to bring the operating handle close to the free edge of the door so as to secure a better leverage in swinging the door than is afforded by mechanisms in which the operating handle is located at a point nearer the door axis. The provision of the slot 22 in the link 20 permits the operation of the latches by suitable automatic fire protective appliances (not shown) without imposing upon such automatic appliances the burden of operating the hand operated device which forms the 60 subject of this invention.

I claim:

1. In a mechanism of the class described, the combination of a door casing, a door hinged to the casing, a latch bar pivoted to the door, a co-operating strike plate secured to the casing in proximity to the free edge of the door, an outer handle pivoted to the door, and connections between said handle and the latch bar for lifting the latter by a backward pull on said handle, a continued movement thereon afterward serving to swing open the door, substantially as described. 70

2. In a mechanism of the class described, the combination of a door casing, a door hinged to the casing, a latch bar pivoted to the door, a co-operating strike plate secured to the casing in proximity to the free edge of the door, an outer handle pivoted to the door, connections between said handle and the latch bar for lifting the latter by a backward pull on said handle, a continued movement thereon afterward serving to swing open the door, and a pressure member on the opposite side of the door in engagement with said latch connections and adapted to actuate the same by an initial thrust and serving to open the door by a continued thrust in the same direction, substantially as described. 80

3. In a mechanism of the class described, the combination of a door casing, a door hinged to the casing, a latch bar pivoted to the door near its free edge, a strike bar secured to the casing in co-operative relation to the pivoted latch bar, a diagonally disposed thrust link pivoted to the latch bar, a slide bar to which the opposite end of the thrust link is pivotally connected, a handle pivoted to the door and adapted when drawn back to impart a movement to the slide plate and a thrust to the link to lift the latch, substantially as described. 100

4. In a mechanism of the class described, the combination of a door casing, a door hinged to the casing, a latch bar pivoted to the door near its free edge, a strike bar secured to the casing in co-operative relation to the pivoted latch bar, a diagonally disposed thrust link pivoted to the latch bar, 110 a slide bar to which the opposite end of the thrust link is pivotally connected, and a handle pivoted to the bar and adapted when drawn back to impart a movement to the slide plate and a thrust to the link to lift the latch, said handle also serving to open the door by a continued pull in the same direction, substantially as described. 120

5. In a mechanism of the class described, the combination of a door casing, a door hinged to the casing, a latch bar pivoted to the door near its free edge, a strike bar secured to the casing in co-operative relation to the pivoted latch bar, a diagonally disposed thrust link pivoted to the latch bar, 125 130

- a slide bar to which the opposite end of the thrust link is pivotally connected, a handle pivoted to the door and adapted when drawn back to impart a movement to the 5 slide plate and a thrust to the link to lift the latch, said handle also serving to open the door by a continued pull in the same direction, a pressure member on the opposite side of the door, and connections between said 10 pressure member and said slide bar for affording a sliding movement to the latter when a thrust is imparted to the pressure member, substantially as described.
6. In a mechanism of the class described, 15 the combination of a door casing, a door hinged to the casing, a latch bar pivoted to the door near its free edge, a strike bar secured to the casing in co-operative relation to the pivoted latch bar, a diagonally dis- 20 posed thrust link pivoted to the latch bar, a slide bar to which the opposite end of the thrust link is pivotally connected, a handle pivoted to the bar and adapted when drawn back to impart a movement to the slide 25 plate and a thrust to the link to lift the latch, said handle also serving to open the door by a continued pull in the same direction, a bell crank pressure member pivoted to the opposite side of the door, and a con- 30 nection between the inner arm of said bell crank member and the slide plate for imparting movement to the slide plate by a thrust applied to the pressure member, substantially as described.
- 35 7. In a mechanism of the class described, the combination of a door casing, a door hinged to the casing, a plurality of latch bars pivoted near the free edge of the door, a bar connecting said latch member, a strike 40 plate for each of the latch bars, an obliquely disposed thrust link pivotally connected to one of the latch bars, a slide plate to which the opposite end of the thrust link is pivoted, a handle arm pivoted to the outer face of the door and provided with an angularly dis- 45 posed finger adapted to engage with a portion of the slide bar and impart movement thereto when the handle is drawn outwardly to effect a lifting of the latch bars, a continued pull on the handle thereafter serving 50 to swing open the door, substantially as described.
8. In a mechanism of the class described, 55 the combination of a door casing, a door hinged to the casing, a plurality of latch bars pivoted near the free edge of the door, a bar connecting said latch member, a strike plate for each of the latch bars, an obliquely disposed thrust link pivotally connected to one of the latch bars, a slide plate to which 60 the opposite end of the thrust link is pro- 65 vided, a handle arm pivoted to the outer face of the door and provided with an angularly disposed finger adapted to engage with a portion of the slide bar and impart move- 70 ment thereto when the handle is drawn outwardly to effect a lifting of the latch bars, a continued pull on the handle thereafter serving to swing open the door, a bell crank pressure member pivoted to the inside of 75 the door, and a link connecting the short inner arm of said bell crank pressure member with the slide plate, a thrust on the pressure member serving to lift the latch members and thereafter swing open the door, substantially as described.

ANDREW C. PREBLE.
